(57) **CLAIM**

I claim the ornamental design for a vase, as shown and described.

DESCRIPTION

FIG. 1 is a bottom plan view of a vase, showing the new design;

FIG. 2 is a top plan view thereof;

FIG. 3 is a front elevation view thereof;

FIG. 4 is a back elevation view thereof;

FIG. 5 is a left side elevation view thereof;

FIG. 6 is a right side elevation view thereof; and,

FIG. 7 is a perspective view thereof.

The broken lines, depicting the inner edge of the top lip and the inside surfaces of the vase, form no part of the claimed design.
